(57) **CLAIM**

The ornamental design for a collapsible/flexible pouring attachment, as shown and described.

DESCRIPTION

FIG. 1 is a top perspective view of the collapsible/flexible pouring attachment in the collapsed position;

FIG. 2 is a perspective view of the collapsible/flexible pouring attachment in an expanded and flexed position;

FIG. 3 is a side view of the collapsible/flexible pouring attachment of FIG. 1 being illustrated with a conventional closure cap;

FIG. 4 is a perspective view of the collapsible/flexible pouring attachment in a collapsed position disposed on a fluid container in addition to the closure cap;

FIG. 5 is a perspective view of the collapsible/flexible pouring attachment disposed on a fluid container and drawn to an expanded and flexed position;

FIG. 6 is a side view of the collapsible/flexible pouring attachment disposed on a fluid container in the collapsed position and covered by a closure cap; and,

FIG. 7 is a bottom perspective view of the collapsible/flexible pouring attachment in the closed position.

The broken lines in the Figures are for illustrative purposes only and form no part of the claimed design.
